UNITED STATES PATENT OFFICE.

HUGO M. GURISCH, OF BALTIMORE, MARYLAND.

CORNER CONSTRUCTION FOR CABINETS.

Application filed August 5, 1926. Serial No. 127,297.

This invention relates to cabinets and has special reference to pressed metal cabinets.

More particularly the invention relates to a corner construction for pressed steel cabinets.

In the manufacture of cabinets of this class it is usual to form the body of the cabinet of one sheet of metal cut and folded to the shape of a box having one side open.

10 The edge of this open side is provided with an outwardly extending flange and to this flange is secured, preferably by spot welding, a flange formed on the inner leg of a U-shaped rim member. It is desirable to 15 form this rim member flange by pressing the metal to shape so that no crack will be formed at the corner and the cabinet door will fit smoothly therein. Experience has shown that it is seldom that such a corner 20 can be formed with the usual thin metal employed without tearing the metal at the corner and making an opening at this point which is inadmissible in construction. Consequently a very high percentage of such 25 rim members have to be discarded as scrap thus adding greatly to the difficulty and expense of manufacture of such cabinets. Moreover, this cannot be obviated by cutting andlapping over as can be done on the outer 30 leg of such a U-shaped rim member because the edges of a cut under these conditions move apart during the bending.

The principal object of the present invention is to provide an improved construction 35 of such a corner wherein the metal of the rim may be pressed to U-shape and yet the corner present a smooth surface on the face against which the door or cover fits.

With the above and other objects in view 40 as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a perspective view showing one 50 front corner of a cabinet constructed in accordance with this invention.

Figure 2 is a section on the line 2—2 thereof.

Figure 3 is a section on the line 3—3 of 55 Figure 2.

Figure 4 is a detail view showing one

corner of the blank from which the rim member is made, the blank being shown slotted to form the rim member and the lines on which it is folded being indicated by 60 dotted lines on the drawing.

Figure 5 is a detail perspective view showing the appearance of the portion of the blank disclosed in Figure 4 as it is when pressed to shape.

65

Figure 6 is a detail view of the filler piece for the gap in the corner as shown in Figure 5.

The body 10 of the cabinet is of the usual 70 sheet metal construction and need not be further described than to say that it is provided with a flange 11 at its open side extending outwardly from the body wall. At the corners this flange laps as at 12.

The rim member is formed from a blank, 75 one corner of which is shown in Figure 4 and it will be noted that this rim member is provided with a face portion 13 and outer wall portions 14 defined from the face portion by the fold lines 15. These lines are 80 continued through each other at the corner, the continuation of one line being by a fold line 16 and the continuation of the other line being by a slit 17 so that a corner piece 18 is provided. Each wall portion 14 has a 85 flange 19 extending along the edge opposite the face portion and defined from the wall by a fold line 20. In the formation of this part of the rim the portions 14 are bent to lie perpendicularly to the face 13 and the corner 90 18 is lapped over the outside of one portion 14. Also the flanges 19 are bent in as shown in Figure 5.

The inner wall is formed by cutting a slit 95 21 in from the re-entrant angle of the blank to the junction of fold lines 22 which define the inner walls 23 from the face 13. Flanges 24 are formed on these inner walls, being defined by fold lines 25. These inner walls are bent perpendicularly to the face 13 and the 100 flanges 24 are bent inwardly as shown in Figure 5 so that they fit beneath the flanges 11 of the body and may there be secured as by spot welding. When thus bent the inner corner of the rim is provided at the side wall with a V-shaped gap 26 which is filled by the filler piece. This filler piece consists of a strip of metal having legs 27 extending at right angles and the angular portion of the filler piece is pressed inwardly along diagonal lines 28 to a displacement equal to 110 the thickness of the metal of the rim, the

lines 28 being so disposed that upon application of the filler piece to the outer faces of the walls 23 at the corner the inner faces of the inwardly pressed portion 29 and of said walls 23 will be flush. Thus this filler piece closes the gap 26 and provides a smooth inside wall for the rim at the corner. The filler piece is preferably spot welded in place.

10 By this means the rim is easily constructed with little chance of producing defects and waste.

There has thus been provided a simple and efficient device of the kind described and for 15 the purpose specified.

Having thus described the invention, what is claimed as new, is:

1. In a cabinet, a rim member of sheet metal having an inner wall provided with a 20 corner gap of V-shape and having inwardly extending flanges on the inner wall, and an angled filler piece extending around the corner against the outer face of said wall and having a portion of the angle pressed inward 25 to fill said gap.

2. In a cabinet, a rim member of sheet metal having an inner wall provided with a

corner gap of V-shape and having inwardly extending flanges on the inner wall, and an angled filler piece extending around the corner against the outer face of said wall and having a portion of the angle pressed inward to fill said gap and lie with the inner faces of the inwardly pressed portion flush with the inner faces of the respective wall portions.

3. In a cabinet, a face member comprising parts disposed at an angle to each other, said parts having inwardly extended walls defining a corner, there being a gap at the corner and an angled filler piece secured against the outer surfaces of said walls and having a distorted portion which fills the corner gap.

4. In a cabinet, a face member comprising parts disposed at an angle to each other, said parts having inwardly extended walls defining a corner, there being a gap at the corner and a filler piece secured against the outer surface of one of said walls and having a 50 distorted portion which fills the gap.

In testimony whereof I affix my signature.

HUGO M. GURISCH.
